UNITED STATES PATENT OFFICE.

VICTOR BRÜNING, OF BERLIN-GRUNEWALD, GERMANY.

PROCESS FOR THE PRODUCTION OF CANALS.

Application filed March 11, 1925. Serial No. 14,751.

Heretofore, canals, particularly ship canals and improvement or drainage canals in bogs and swamps, were produced by manual labor by means of digging or the like. However, 5 that manner of working is often impossible and in any case very expensive and tedious. For such working there are required many laborers who are very often difficult to obtain and the work requires years for the 10 practical completion of a long canal.

The present known dry and wet dredging or pumping apparatus as used for building harbor works and channels, particularly in marshy districts are also not suitable, because 15 the wet material pumps and dredges cannot handle thick, heavy, boggy material, being only suitable and efficient when the material being dealt with, is almost wholly water. The dry material dredgers have 20 great labor costs and also often require tracks or rails on which to move the heavy machinery of which they are composed. It is often necessary to preliminarily remove much water. It often also happens that 25 these less efficient and heavy machines sink in the yieldable ground or often when set up on or near the site being worked, fall into the bed of the canal. In addition, the material dug or dredged out must often be 30 removed by means of special transporting apparatus at relatively high cost.

A purpose of this invention is to carry away the soil in which the canal is being built with a minimum of water, power, expense and labor.

These particular defects are overcome by the present invention, which, by means of its great efficiency, permits of making long canals, even in uninhabited and inaccessible 40 regions, at relatively slight labor costs and in short periods of time.

The object of the present process is an essential reduction in the cost and simplification in the work, and comprises an entirely 45 different and novel method. The characteristic features of the process consist in that the material in the future canal bed is separated from the material which is to remain permanently in place either by a stream or 50 streams of high pressure water or by explosive means, and such material is then mixed with water at little or no pressure by means of the high pressure stream, while the place of operating is maintained sepa-

rated from the completed portion of the 55 canal, for the purpose of making the mixture of earth and water exactly suitable for pumping by a suitable pumping apparatus, which apparatus forces the mixture away by any forming conveying means such as 60 pipes, ditches, wagons, boats, or the like, either directly or indirectly to the place desired.

In the use of the present process, the removed material can also be conveyed to any 65 desired point, for example, it may be utilized for filling in depressions in the earth, or in any other manner. The removed material, alone or in admixture with other material may also be used for making the canal 70 banks or for other building purposes, the removed material being in general, rich in peaty matter so that it may be compressed, alone or in admixture with other substances into artificial lumber or wall boards. The 75 process can be carried out in different ways, according to conditions that are met, or dependent on the character of the material in which the canal is being built, dimensions 80 of the canal and direction thereof, use of the removed material, etc.

In the drawings there is shown an exemplary embodiment of the process and Fig. I represents a fragmentary, diagrammatic, longitudinal section of a canal during construction, employing the process of this invention:

Fig. II is a similar plan view of Fig. I; and

Fig. III is a plan view showing the use 90 of a plurality of installations simultaneously employed in forming a canal.

Fig. IV is a cross section showing a detail of the canal in which a wall of retained material is shown separating a finished portion of the canal from the working place.

In the drawing there is shown the movable nozzles or spray apparatus 1 and 2 which operate at both sides, at the head of the canal bed which is being formed, and the suction pump apparatus is shown at 3 in the bed of the canal.

The material being removed is conducted through a flexible or jointed pipe or conduit 10 from the pump 3 to the point at which it is to be deposited. The water which is put under pressure is preferably carried off from that part of the canal already completed, but

it may also be obtained from wells or other sources. The point at which the water is removed is designated by 5 in Figs. I, II and III. The water pressure pump 6 obtaining water from point 5 forces this water under great pressure through the pipe 7 to a manifold 8 and from 8 by flexible hose 9 to the nozzles 1 and 2. The number of these nozzles may be as great as desired or found necessary.

A low pressure pump 12 obtaining water from the already completed canal forces water into the work place to be there mixed with the high pressure water and the material which is to be carried away. This additional water can also be taken out of the completed canal and be conducted through passages or openings 30 in the gates 15 in such wise that the quantity of the additional water can be regulated. No matter in which manner the additional water is supplied the amount is completely regulatable so that little, much or no additional water at all is added to the mixture, the purpose of the added water being to regulate the moisture content of the final pumpable mixture. The complete power plant 13 may be carried, as shown, on a barge 11, all pumps and other apparatus being supplied with power from this plant.

The pumps 3 may be carried by movable cranes or derricks 14 located at one end of the barge. The barge itself floats in the water of the completed part of the canal, and the cranes 14 support the pumps 3 over and beyond the temporary removable walls or gates 15. The walls or gates 15 are placed from time to time, across the canal channel as shown in the figures, and serve to keep the water in the completed part of the canal away from the work under operation.

Instead of walls and gates 15, dikes or dams of earth 15' may be used to separate the completed part of the canal from the working part. These dams or dikes can later when the work is sufficiently progressed, be readily removed either by explosive means or also by use of the high pressure nozzles.

The addition of a regulated amount of water is of particular importance since if the water was to flow without regulation to the removed material, the result would not be successful. An essential feature of the process is the separation of the completed part of the canal from the place under operation, so that the removed material can be worked up in the desired manner and to the proper consistency with the water under high pressure and the additional regulating water. Only by means of this separation can the desired result be attained.

In Fig. III there is illustrated an arrangement whereby a plurality of installations of

nozzles and pumps 3 are simultaneously employed along the canal site. A plurality of installations may also be placed side by side.

With long distances between the points at which the water to the pressure pumps is being removed and the nozzles which are tearing down the earth, it may become desirable to interpose one or more low pressure pumps in the pipes 7 in order to maintain the necessary pressure.

The mass drawn up by the suction pumps 3 may be carried away through flexible or jointed movable pipe lines 18, laterally to one or both sides of the canal and there deposited through outlets in the pipe 18. Obviously the mass can be carried off in any desired manner, for instance, as shown in Fig. III where a second barge 20 is illustrated into which the mass is poured to be transported either by means of it, or out of which barge it may, by any desired manner, be removed out of it at any desired location.

In Figs. I and II the movable portion of gates 15 by which the amount of water flowing from the completed part of the canal to the work place, is regulated, is shown at 30.

According to the particular conditions the suction pump and other machines or parts of the same may also be placed above the canal bed, for example between the nozzles 1 and 2 or along the side of the canal site. Where the soil or material in which the canal is to be dug is very dense, explosives or mechanical means may be used in addition to the high pressure water for separating the material which is to be removed from that which is to remain. Similarly mechanical means may also be used to assist in the working up of the mass to pumpable condition.

The present process is adapted for constructing canals in any character of soil.

Having thus described my invention what I desire to claim is:

1. A process for building ship, drainage, and similar canals, which comprises separating, in a working place, the material which is to be removed from that which is to remain by means of water under pressure, mixing the separated material in any desired manner with water of exceedingly low pressure by means of the high pressure water in the working place, completely separating the working place from the completed part of the canal, pumping the resulting mixture out of the working place and conveying it to a desired locality.

2. A process for building ship, drainage, and similar canals, which comprises separating, in a working place, the material which is to be removed from that which is to remain by means of high pressure streams of water, mixing the separated material in any desired manner with water of exceedingly low pressure by means of the high

pressure water in the working place, completely separating the working place from the completed part of the canal, pumping the resulting mixture out of the working place and conveying it to a desired locality.

3. A process for building ship, drainage, and similar canals, which comprises separating, in a working place, the material which is to be removed from that which is 10 to remain by means of water under pressure, mixing the material in any desired manner with the high pressure water in the working place, completely separating the working place from the completed part of the 15 canal, pumping the resulting mixture out of the working place and conveying it to a desired locality.

4. A process for building ship, drainage, and similar canals, which comprises separating, in a working place, the material which is to be removed from that which is 20 to remain by means of water under pressure assisted by explosive means, mixing the material in any desired manner with water of 25 exceedingly low pressure by means of the high pressure water in the working place, completely separating the working place from the completed part of the canal, pumping the resulting mixture out of the working 30 place and conveying it to a desired locality.

5. A process for building ship, drainage, and similar canals, which comprises separating, in a working place, the material which is to be removed from that which is to 35 remain by means of water under pressure assisted by mechanical means, mixing the

material in any desired manner with water of exceedingly low pressure by means of the high pressure water in the working place, completely separating the working place 40 from the completed part of the canal, pumping the mass out of the working place and conveying it to a desired locality.

6. A process for building ship, drainage, and similar canals, which comprises separating, in a working place, the material which is to be removed from that which is to remain, working up the material to be removed with water to render it pumpable, maintaining the material being worked up 50 completely separate from the completed part of the canal, and then pumping out the resulting mixture from the working place and conveying it to a desired locality.

7. A process for building ship, drainage, and similar canals, comprising, washing away material to be removed by water jets in a working place, and separating in a substantially water tight manner, the working place from an adjacent finished portion of 55 the canal.

8. A process for building ship, drainage, and similar canals, comprising, washing away material to be removed by water jets in a working place, and completely separating the working place from the finished portion of the canal by a substantially water 60 tight wall.

In testimony whereof I have signed my name to this specification.

VICTOR BRÜNIG.
